ATTORNEY

UNITED STATES PATENT OFFICE

HARRY BORDEN, OF BROOKLYN, NEW YORK

WRINKLEPROOF RUG EDGE REENFORCING BINDING

Refiled for abandoned application Serial No. 467,834, filed July 14, 1930. This application filed July 29, 1932. Serial No. 626,185.

This invention relates to new and useful improvements in a wrinkle proof rug edge reenforcing binding.

The present application is a refile of my 5 abandoned application filed on July 14, 1930, Serial Number 467,834.

The invention has for an object the provision of a device of the class mentioned which is of simple durable construction, de- 10 pendable in use and efficient in action, and which can be manufactured and sold at a reasonable cost.

The invention proposes a cloth casing consisting of a narrow strip attached along its 15 edges along the center of a broad strip so that the casing may be attached at its edges along the edges of the bottom side of a rug, and a flexible strip within the pocket formed by said strips.

20 The invention also proposes means for changing the flexibility of said flexible strip.

For further comprehension of the invention, and of the objects and advantages thereof, reference will be had to the following de- 25 scription and accompanying drawing, and to the appended claims in which the various novel features of the invention are more particularly set forth.

In the accompanying drawing forming a 30 material part of this disclosure:—

Fig. 1 is a fragmentary rear elevational view of a rug provided with bindings according to this invention.

Fig. 2 is a fragmentary sectional view 35 taken on the line 2—2 of Fig. 1.

Fig. 3 is a view similar to Fig. 2, but illustrating a modified way of attaching the binding.

Fig. 4 is a fragmentary rear elevational 40 view of another form of rug provided with the binding.

Fig. 5 is a fragmentary enlarged elevational view of a binding constructed according to modified form.

45 Fig. 6 is a sectional view taken on the line 6—6 of Fig. 5, but shown applied upon a rug.

The wrinkle proof rug edge reenforcing binding comprises a cloth casing 10 consist- 50 ing of a narrow strip 11 attached along its

edges to the center of a broad strip 12 so that the casing may be attached at its edges along the edges of the bottom side of a rug, and a flexible strip 13 within the pocket formed by said strips.

Preferably the narrow strip 11 should be made from white cloth and stitches 14 used for securing it to the broad strip 12. The broad strip should preferably be made of gray or other colored cloth so that it will 55 not show dirt. Stitches 15 serve to connect the edges of the casing 10 upon a rug 16. The provision of a narrow and broad strip provides a casing which is relatively broad as compared with the narrow flexible strip giving 60 sufficient room for attachment upon a rug and presenting a very efficient construction. Obviously, the narrow strip could have been as wide as the wide strip, but this would 65 cost slightly more in that more material would be used and no additional function gained. Furthermore, the provision of a narrow strip superimposed upon a wide strip exposes for use a single thickness of material along the edges. This allows easy at- 70 tachment of the strips in place in that the stitches or other means used in the attaching need go through but a single piece of material only. The flexible strip 13 should 75 preferably be made from spring steel, though 80 this is not intended as a limitation since various compositions may be used.

In Fig. 1 a corner construction has been shown of the rug 16 with binding strips applied. One binding strip has been shown 85 extending from the corner 17 of the rug longitudinally along one edge. These bindings are attached so that the narrow strips 11 are disposed adjacent the rear side of the rug as shown in Fig. 2. Closure stitches 18 close 90 the ends of the binding so as to hold the flexible strips 13 against displacement. In Fig. 3 a modified arrangement has been shown in which the narrow strip 11 is disposed remote to the rug 16.

The broad strip 12 may also be doubled to 95 form a pocket in which the flexible strip 13 may be inserted.

In Fig. 4, an elliptical shaped rug 19 has 100 been shown provided with binding strips

according to this invention. These binding strips are shown applied upon the rear of the rug and longitudinally adjacent the edges. One piece of binding may be used and completely encircle the edge so that the ends are adjacent each other. If desired, several pieces of arcuate binding strips may be attached in a line around the periphery of the rug. These pieces may be slightly spaced from each other so that bending of the rug is possible. The binding strip may be made of arcuate shape or may be made with sufficient flexibility to be bent into the arcuate shape. If made so as to bend into arcuate shape, it is requisite that the flexible strip used in the binding be elastic so that it may bend laterally and thus be sewed in place to maintain the bent form.

In the modified form of the device illustrated in Figs. 5 and 6, a means has been shown for changing the flexibility of the flexible strip within the binding. This means comprises a plurality of lateral projections 20 from one edge of the flexible strip 13 and extending through spaced openings 21 formed in the narrow strip 11, when the binding is placed with the narrow strip outwards and formed in broad strip 12 when the binding is placed with the broad strip outwards. The free edges of the projections 20 are of dovetail shape as shown in Fig. 6, and a flexible wire 22 with a dovetailed groove is slid upon the dovetailed projections so as to coat with the flexible strip 13 and produce a resultant flexibility. To change the flexibility of the strip, it is merely necessary to slip the flexible wire off. Other adjustments may be made by replacing the flexible wire with wires of different diameter, that is, different degrees of flexibility.

It is to be understood that the flexible strip 13 may be of any desired composition, shape, thickness and length to correspond with the shape of rectangular, oval or any other shaped rug.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what

I claim as new, and desire to secure by United States Letters Patent is:—

1. In a wrinkle proof rug edge reenforcing binding, a cloth casing for a flexible strip consisting of a narrow strip attached along its edges along the center of a broad strip so that the casing may be attached on a single thickness edge along the edge of the bottom side of a rug.

2. In a wrinkle proof rug edge reenforcing binding, a cloth casing for a flexible strip consisting of a narrow strip attached along its edges along the center of a broad strip so that the casing may be attached on a single thickness edge along the edge of the bottom side of a rug, the attachment between the narrow and broad strips being accomplished by a longitudinal row of stitches.

3. A wrinkle proof rug edge reenforcing binding, comprising a cloth casing consisting of a narrow strip attached along its edges along the center of a broad strip so that the casing may be attached at its edges along the edges of the bottom side of a rug, a flexible strip within the pocket formed by said strips, and means for changing the flexibility of said flexible strip.

4. A wrinkle proof rug edge reenforcing binding, comprising a cloth casing consisting of a narrow strip attached along its edges along the centre of a broad strip so that the casing may be attached at its edges along the edges of the bottom side of a rug, and a flexible strip within the pocket formed by said strips, said flexible strip being also elastic for lateral bending into arcuate shapes.

5. A wrinkle proof rug edge reenforcing binding, comprising a cloth casing consisting of a narrow strip attached along its edges along the center of a broad strip so that the casing may be attached at its edges along the edges of the bottom side of a rug, a flexible strip within the pocket formed by said strips, and means for changing the flexibility of said strip, comprising spaced lateral projections from one edge of the flexible strip extending through openings in one of the strips of said casing, and a dovetailed wire removably engaged upon said projections.

In testimony whereof I have affixed my signature.

HARRY BORDEN.
